CLAIM

We claim the ornamental design for a filtration device, as shown and described.

DESCRIPTION

FIG. 1 is an isometric view, from the top left, of the filtration device.

FIG. 2 is an isometric view, from the bottom right, of the filtration device.

FIG. 3 is an elevation view from the left side of the filtration device.

FIG. 4 is an elevation view from the right side of the filtration device.

FIG. 5 is an elevation view from the front of the filtration device.

FIG. 6 is an elevation view from the back of the filtration device.

FIG. 7 is a plan view from the top of the filtration device.

FIG. 8 is a plan view from the bottom of the filtration device; and,

FIG. 9 is a plan view from the top of the filtration device without a handle.

The broken lines in the drawings depict portions of the filtration device that form no part of the claimed design.
